UNITED STATES PATENT OFFICE.

NEWELL B. PARSONS, OF CHICAGO, ILLINOIS, ASSIGNOR TO BELDEN MANUFACTURING COMPANY, OF CHICAGO, ILLINOIS, A CORPORATION OF ILLINOIS.

ATTACHMENT FOR TELEPHONES.

936,254.

Specification of Letters Patent.

Patented Oct. 5, 1909.

Continuation of application Serial No. 322,866, filed June 22, 1906. This application filed January 6, 1908. Serial No. 409,385.

To all whom it may concern:

Be it known that I, NEWELL B. PARSONS, a citizen of the United States of America, and a resident of Chicago, county of Cook, and 5 State of Illinois, have invented a new and useful Improvement in Attachments for Telephones, of which the following is a specification.

My invention pertains to attachments for 10 telephones, for holding a writing pad suitably for the convenience of the telephone user.

In my present invention I have provided 15 means for holding a writing pad and adapted to be attached to wall telephone sets not having the usual writing shelf.

Three figures of drawings accompany this 20 description, in which—

Figure 1 shows a front view of my attachment, Fig. 2 shows a side view and Fig. 3 shows a side view of my attachment as applied to a telephone equipment of the class indicated above.

The first or pad-holding element consists 25 of a bracket 1, a paper shelf 2, screw-threaded rivet-posts 3 3 holding the bracket and shelf together, and means for holding a pad of paper upon the shelf. In the figures, the means employed consists of extension members of the rivet-posts 3 3 screw-threaded to receive the nuts 4 4 adapted to clamp the bar 5 and the pad 6, both of which are slipped upon the extension posts before the nuts 4 4 are applied. The bracket 1 is 30 adapted to engage the front of the telephone box, and an extension arm 1' integral with the bracket 1 extends backward beyond the edge of the main portion of the bracket 1 and turns upwardly in hook form to engage 35 the back surface of the door of the telephone box by passing around the lower projecting edge of the door.

The second or clamping element consists 40 of a rod 7 whose upper end is formed into a hook shape as at 8 to engage the upper projecting edge of the door of the telephone box and whose lower end is threaded to receive a wing-nut 9 after passing loosely through the bracket 1, whereby the hook 8 45 and the bracket 1 may be drawn together to clamp the door of the telephone box between them.

It will be noted that, as the wing-nut 9

is tightened upon the rod 7 after being applied to the telephone door as shown in Fig. 55 3, the extension arm 1' first will engage the lower edge of the door, and the pad-holding element as a whole, being a rigid unit with the bracket 1, then will swing upon the contact of arm 1' and the edge of the door until 60 the hook end of extension 1' engages the back surface of the door and until the upper or main portion of the bracket 1 engages the front surface of the door, when further movement will be impossible and further 65 turning of the wing-nut 9 will make the paper shelf firm in its position by placing a stress upon the structural parts of the attachment. The pad thus will be held rigidly in position, without possible motion 70 in any direction whatever, and inclined at an angle depending partly upon the conformation of the bracket 1 and partly upon the thickness of the door of the telephone box.

It is found that, when only a limited 75 amount of motion is permitted between the two elements as above described, this attachment is well adapted to mount upon telephone boxes having projecting edges, the complete attachment gripping the upper and 80 lower surfaces of the box and bearing also upon the front surface in a manner that provides a rigid and reliable mounting for the pad of paper.

I do not wish to limit myself in all respects to the exact details herein shown and described, and I understand that many modifications may be made without departing from the spirit and scope of my invention.

Having thus described my invention, what 90 I claim as new and desire to secure by United States Letters Patent is:

1. In an attachment for a telephone box door, a pad-sustaining bracket comprising an inclined plate having at its upper part 95 an edge engaging the front surface of the telephone door and having at its lower part an extension extending back below and beyond the lower edge of the door and turning upward in hook form and engaging the 100 back surface of the door; and a bolt engaging the upper edge of the door and drawing the two described edges of the bracket against the two described surfaces of the door, substantially as described.
2. In an attachment for a telephone door,

a vertical clamping rod hooking over the top edge of the door; a pad-bracket having two door-engaging wing-like arms, one engaging the front surface of the door and 5 the other engaging the back surface of the door, said arms being perforated for the passage of said clamping rod loosely whereby an alinement of the bracket by engagement with the rod is avoided and alinement

of the bracket by engagement with the door 10 is permitted, substantially as described.

Signed by me at Chicago, county of Cook and State of Illinois, in the presence of two witnesses.

NEWELL B. PARSONS.
